UNITED STATES PATENT OFFICE.

ALBERT JANSON, OF NEW YORK, N. Y.

DESIGN FOR A MOLDING.

47,881.

Specification for Design.

Patented Sept. 28, 1915.

Application filed July 19, 1915. Serial No. 40,781. Term of patent 7 years.

To all whom it may concern:

Be it known that I, ALBERT JANSON, a citizen of Finland, and resident of the borough and county of Bronx, in the city and the State of New York, have invented a new, original, and ornamental Design for Moldings, of which the following is a specification, reference being had to the accompanying drawing, forming a part thereof.

In the said drawing:—Figure 1 is a front view of a molding, showing my new design; and Fig. 2 is an edge view of the same.

I claim:—

The ornamental design for a molding as shown.

In testimony whereof I have signed my name to this specification in the presence of two subscribing witnesses.

ALBERT JANSON.
